ALBERT D. TRENOR, OF NEW YORK, N. Y., ASSIGNOR TO JOHN HAYS HAMMOND, JR., OF GLOUCESTER, MASSACHUSETTS.

SYSTEM FOR PREDIRECTING TORPEDOES.

1,408,147.

Specification of Letters Patent. Patented Feb. 28, 1922.

Application filed February 27, 1918, Serial No. 219,435. Renewed May 23, 1921. Serial No. 471,971.

To all whom it may concern:

Be it known that I, ALBERT D. TRENOR, a citizen of the United States, and a resident of the city of New York, in the county of

5 New York and State of New York, have invented certain new and useful Improvements in Systems for Predirecting Torpedoes, of which the following is a specification.

10 Some of the objects of this invention are to provide in a system for predirecting torpedoes improved means for predirecting a torpedo at a moving target in such a manner that the speed and direction of movement 15 of the target and the normal speed of the torpedo may be included automatically as factors in predirecting the torpedo in response to the movement of the telescope or other sighting or aiming device; and to provide other improvements as will appear 20 hereinafter.

In the accompanying drawings Fig. 1 is a diagrammatic side elevation partly in vertical section of a system constructed in accordance with this invention for predirecting torpedoes; Fig. 2 is a top plan view of a portion of the same; and Fig. 3 is a diagram explanatory of the operation of the system.

25 Referring to the drawings, one embodiment of this invention comprises a system for predirecting torpedoes, which is shown as arranged upon a torpedo boat 9 or other basal support to predirect the automatic steering mechanism 10 of a torpedo 15 while the torpedo is in an initial position in a torpedo tube 16 which is carried by and fixed with respect to the torpedo boat 9. In the form of this invention shown in the drawings the 30 torpedo tube 16 is so arranged that its longitudinal axis is substantially perpendicular to the longitudinal axis of the torpedo boat 9, but it is to be understood that the torpedo tube might be arranged in any other suitable position, with a corresponding initial adjustment of the automatic steering mechanism 10 of the torpedo 15. This improved system includes a sighting or aiming unit 20, an auxiliary mechanism 25 and a stabilizing device 30. The sighting unit 20 is operatively connected to the automatic steering mechanism 10 of the torpedo 15 through the auxiliary mechanism 25, and the stabilizing device 30 is arranged to be rendered effective, when desired, to compensate for the ro-

tary movement of the torpedo boat 9 about a vertical axis while the predirecting system is under the control of the telescope 40, as will appear hereinafter.

The sighting unit 20 includes a normally vertical shaft 35 which is arranged to rotate about an axis coincident with its longitudinal axis and fixed with respect to the torpedo boat 9 or other basal support upon which the shaft 35 is mounted, the lower portion of the shaft 35 being rotatably supported for instance in a fixed bearing 36 and being held against longitudinal movement therein. Pivotedly connected to the upper end of the shaft 35 to swing in respect thereto about a normally horizontal axis is a telescope or other sighting instrument 40 which is arranged in such a position upon the boat or other support that it is approximately in vertical alinement with the torpedo tube 16, and that it may be conveniently directed towards an enemy vessel or other target towards which it is desired to predirect the torpedo 15. Rigid with the shaft 35 is a pointer 41 which cooperates with a dial 42 which surrounds and is coaxial with the shaft 35 and which is rigidly secured to a platform or base 43 which is fixed with respect to the torpedo boat 9.

The auxiliary mechanism 25 includes a rigid frame comprising a flat, rigid base plate 45 which is arranged in any convenient position upon the torpedo boat 9. The base plate 45 is bounded upon one side by a straight edge 46 and upon its other side by a curved edge 47 which is circular in form and concentric with a point 48 which is upon the base 45 and is spaced a slight distance from the straight edge 46. The base plate 45 is provided along its curved edge 47 with a rim or wall 49 integral with or rigidly secured to the base plate 45 and perpendicular thereto. This rim 49 is provided upon its inner surface and along its upper edge with a segmental marginal rib 50 which is integral with the rim or rigidly secured thereto and arranged in a plane parallel to the base plate 45 for a purpose hereinafter described, the upper edge of the rib 50 being flush with the upper portion of the edge of the rim 47. Spaced above the rib 50 and arranged in a plane parallel to the base plate 45 are two rigid parallel tracks 55 and 56 which are terminally secured to the rim 49 by which the tracks are held in fixed posi-

tions. The track 55 is provided with graduations 57 corresponding to various rates of speed of the target as measured in knots.

Carried by the base 45 and forming a part of the auxiliary mechanism 25 is a primary transmission device 60 including a flat, rigid supporting plate 61 which is arranged in a plane parallel to but spaced above the base-plate 45, but below the plane of the rib 50 which is held in a fixed position with respect to the base 45 by means of two rigid brackets 62 and 63 secured to and projecting upwardly from the base 45. Extending snugly but rotatably through the supporting plate 61 is a normally vertical shaft 65 which projects above and below the plate 61 and which is held against movement longitudinally with respect thereto. This shaft 65 is arranged to rotate about an axis coincident with its longitudinal axis and which is perpendicular to the base 45 and coaxial with the rim 47. Rigidly secured to the upper end of this shaft 65 is a primary arm or element 66 which extends in a plane parallel to the base 45 and which includes the segmental rib 50. The outer end of this arm 66 is provided with a yoke 67 rigid therewith which engages snugly but slidably over the segmental rib 50 and restrains the outer end of the arm 66 to move in a predetermined path. The inner end of the arm 66 is provided with a pointer 68 rigid therewith and arranged in longitudinal alinement therewith, and this pointer is arranged to cooperate with a dial 69 provided with marginal graduations, which loosely surrounds the shaft 65 and is rigidly secured to the upper surface of the fixed plate 61. Beneath the plate 61 and surrounding the vertical shaft 65 is a gear 70 which is held against movement longitudinally of the shaft 65, but which is free to rotate with respect thereto. Depending from this gear 70 and rigid therewith is a lug 71 which carries a beveled pinion 72 which is arranged to rotate freely with respect to the lug 71 about an axis fixed with respect thereto and extending perpendicular to and intersecting the axis of rotation of the vertical shaft 65. This pinion 72 engages a corresponding beveled gear 73, which is fixed upon the lower end of the shaft 65, and also engages a beveled gear 74 which is fixed upon the upper end of a shaft 75 which is arranged in longitudinal alinement with the shaft 65 and which is supported in a bearing provided therefor in the base 45 to rotate with respect to the base 45 and to be held against longitudinal movement with respect thereto. Spaced slightly above the base 45 and surrounding and rigidly secured to the shaft 75 is a dial 76 which is provided with marginal graduations 77 which are arranged to cooperate with corresponding fixed graduations 78 upon the base 45 to

indicate the position of location of the shaft 75. Also surrounding and rigidly secured to the shaft 75 is a gear 79 which is arranged to be rotated by a pinion 81 which is arranged to be rotated about a fixed vertical axis by means of an electrical motion repeating device 80 of any well known or suitable construction.

The repeating device 80 is arranged to be actuated by a corresponding electrical transmission device 85 to which it is electrically connected by means of a four-wire cable 86 including a return wire 87 arranged to be energized by a battery 88 and controlled by a switch 89. The transmission device 85 is fixed in position and is actuated by a pinion 90 which is actuated by a gear 91 which surrounds and is rigid with the shaft 35 carrying the telescope 40.

The auxiliary mechanism 25 also includes a secondary transmission device 95 which comprises a rigid rectangular casing 96 which is carried by two pairs of sliders 97, 97 and 98, 98 which are rigid therewith and which are slidably mounted upon the two tracks 55 and 56 respectively in such a manner as to restrain the casing 96 to move in a predetermined path parallel to the base 45 and spaced above the segmental rib 50. The casing 96 includes a top plate 100 and a bottom plate 101 which are arranged in planes parallel to the base 45. Extending snugly but rotatably through the bottom plate 101 is a vertical shaft 105 which is held against longitudinal movement with respect to the bottom plate 101. Arranged below the bottom plate 101 and rigidly secured to the lower end of the shaft 105 is a secondary arm or element 110 which extends in a direction parallel to the base 45 and which is spaced slightly above and normally crosses the arm 66 of the primary transmission device 60. This arm is provided with a series of transversely extending graduations 111 which read from the longitudinal axis of the vertical shaft 105 or axis of oscillation of the arm 110, and which correspond to the normal speed or rate of movement of the torpedo in knots for a unit of time. Arranged within the casing 96 and loosely surrounding the shaft 105 is a gear 115 which has rigidly secured thereto and projecting upwardly therefrom a lug 116 which carries a beveled pinion 117 which is arranged to rotate about an axis fixed with respect to the lug 116 and intersecting and perpendicular to the axis of rotation of the vertical shaft 105. This pinion 117 engages a beveled gear 118 which is rigidly secured to the upper end of the shaft 105 and also engages a beveled gear 119 which is rigidly secured to the lower end of a vertical shaft 120 which is in longitudinal alinement with the shaft 105 and which projects snugly but rotatably through the top plate 100. Rigidly

secured to the upper end of this shaft 120 is a pointer 121 which is arranged to co-operate with a series of graduations 122 provided therefor upon a dial 123 loosely surrounding the shaft 120 and which is rigidly secured to the upper surface of the top plate 100. Extending loosely through an axial opening provided therefor in the shaft 120 is a stem 125 secured at its lower end to the upper end of the lower shaft 105. Rigidly secured to the upper end of this stem 125 is a pointer 126 which is arranged to co-operate with a series of marginal graduations 127 provided therefor on the dial 123. Surrounding and rigidly secured to the shaft 120 is a gear 140 which engages a pinion 141 which actuates an electrical motion transmission device 142. The transmission device 142 is electrically connected to a corresponding electrical repeating device 143 by means of a four-wire cable 144 including a return wire 145 energized by a battery 146 and controlled by a normally closed switch 147. The repeating device 143 actuates a pinion 148 which actuates a gear 149 through which the automatic steering mechanism 10 of the torpedo 15 may be adjusted so as to pre-direct the torpedo 10 in any desired direction.

For operatively connecting the two arms 66 and 110, the arm 110 is provided with a sleeve 150 which is slidably adjustable longitudinally of the arm 110 and which may be held fixedly in any desired position of adjustment by means of a set-screw 151 which is threaded through the sleeve 150 and which engages against the arm 110. Rigidly secured to this sleeve 150 and depending downwardly therefrom is a pivot 152 which engages snugly but rotatably in an opening provided therefor in the upper wall of a hollow rectangular carrier 155 which is mounted upon two pairs of rollers 156, 156 and 157, 157 which are arranged to rotate respectively about vertical axes fixed with respect to the carrier 155 and which engage opposite sides of the arm 66 to permit the carrier 155 to be moved freely longitudinally of the arm 66 and in a predetermined path with respect to the arm. The pivot 152 is so arranged that its longitudinal axis is vertical and extends at all times through a line which extends longitudinally and centrally of the arm 66. By this arrangement when the sleeve 150 is fixed in any desired position of adjustment upon the arm 110, the arm 66 may be rotated in either direction about the longitudinal axis of the shaft 65 with a minimum of resistance on the part of the carriage 155.

To compensate for any rotary movement of the torpedo boat about a vertical axis, after the parts of the predetermined system have been initially adjusted and while the parts of the system are under the control of the telescope 40, the two gears 70 and 115 are arranged to be simultaneously controlled by the stabilizing device 30. The stabilizing device 30 includes a gyroscope 180 of any well known suitable construction provided with a shaft 181 arranged to be held by the gyroscope against rotation in space about a normally vertical axis fixed with respect to the torpedo boat. A gear 182 is fixed to the shaft 181 and actuates a pinion 183 which controls an electrical motion transmission device 185 which is connected by means of a four-wire cable 186 and branch four-wire cable 187 to the two repeating devices 175 and 176. The four-wire cable 186 includes a return wire 187 which is energized by a battery 188 and which is controlled by a switch 189. The repeating device 175 rotates a shaft 195 which projects snugly but rotatably through the plate 61 and which has secured to its upper end a pointer 196 which cooperates with a graduated dial 197 loosely surrounding the shaft 195 and fixedly secured to the upper surface of the plate 61. A pinion is rigidly secured to the shaft 195 and engages the gear 70. The repeating device 176 actuates a shaft 198 which projects snugly but rotatably through the plate 100 and which has secured to its upper end a pointer 200 which cooperates with a graduated dial 201 which loosely surrounds the shaft 198 and which is fixedly secured to the upper surface of the plate 100. A pinion 205 is rigidly secured to the lower end of the shaft 198 and engages the gear 115. The arrangement is such that when the switch 189 is closed the transmission device 185 under the control of the gyroscope 180 acts upon the repeating devices 175 and 176 to hold the corresponding gears 70 and 115 against rotation in space as long as the torpedo boat 9 moves on a straight course.

When the torpedo boat 9 is diverted from a given course through a given angle in either direction, the gyroscope 180 acts through the gear 70 to rotate the arm 66 with respect to the torpedo boat 9 through an equal angle and in the same direction. If the target were stationary and the telescope 40 were kept pointed upon the target during this rotation of the torpedo boat, the telescope 40 would act through the repeater 80 to rotate the arm 66 with respect to the torpedo boat 9 in an opposite direction and through an equal angle. The combined result would be that if the target remained stationary the arm 66 would remain in a fixed position with respect to the torpedo boat 9, but assuming that the target is moving in a given direction at a given rate of speed as hereinbefore described and as shown in Fig. 3, and that the telescope 40 is kept aimed upon the target during the rotation

of the torpedo boat 9, then the combined result of the action of the gyroscope 180 and of the telescope 40 would be to rotate the arm 66 with respect to the torpedo boat 9 through an angle equal to and in the same direction as the angle through which the telescope 40 is rotated in space in following the target. Also during the rotation of the torpedo boat 9 through a given angle in a given direction, if the target were stationary, the gyroscope 30 would act through the repeater 176 to cause the gear 140 to rotate through an equal angle and in the same direction and this gear 140 acting through the transmitter 142 would rotate the gear 149 in a corresponding direction to readjust the steering mechanism 10 in the torpedo 15 in such a manner as to compensate for the rotation of the torpedo boat 9. But as the target is moving as hereinbefore described, the arm 110 will be consequently rotated as a result of the rotation of the arm 66 and this rotation of the arm 110 will be imposed upon the gear 140 in addition to the rotation of the gear 140 caused by the action of the gyroscope 180, this added rotation of the gear 140 being transmitted by the transmitter 142 to the repeater 143 to readjust the steering mechanism 10 in such a manner as to compensate for the movements of the target. The steering mechanism 10 will therefore be adjusted in such a manner as to compensate for any rotary movement of the torpedo boat 9 and also to compensate for any movement of the target at a known rate in a known direction, and so as to predirect the torpedo 15 in such a manner that if the torpedo should now be launched it would travel at a given rate along such a line that when the target reached the point of intersection of the line of travel of the target and the line of travel of the torpedo, the target would be struck by the torpedo.

In the operation of this improved system when it is desired to predirect the torpedo 15 in such a manner as to strike a target 235 located at a known point 236 and moving along a known line of direction 237 at a known rate, the switch 147 is opened, and the gear 149 which controls the steering mechanism 10 of the torpedo is set in a zero position which in this case would cause the torpedo to move in a course perpendicular to the longitudinal axis of the torpedo boat 9. The arm 110 is then set perpendicular to the line joining the axes of oscillation of the two arms 66 and 110, as indicated by the pointer 126 on the graduations 127, the pointer 126 and the zero mark on the dial 127 being so arranged that when the arm 110 is thus set the pointer 126 will register with the zero mark of the dial 127. The gear 115 is then rotated into a zero position as indicated by the pointer 200 on

the dial 201 which may be any position of the gear 115 depending upon an arbitrary arrangement of the pointer 200 and the dial 201. The gear 140 will then be in a given position and the pointer 121 and the dial 123 are so arranged that when the gear 140 is in the given position the pointer 121 will register with the zero mark of the dial 123. The switch 147 is then closed. The telescope 40 is then pointed in a direction perpendicular to the longitudinal axis of the torpedo boat 9, as indicated by the pointer 41 on the scale 42, the pointer 41 and scale 42 being so arranged that when the telescope is thus pointed the pointer 41 will register with the zero mark of the scale 42. The arm 66 is then moved to a position perpendicular to the line joining the axes of oscillation of the two arms 66 and 110, as indicated by the pointer 68 on the scale 69, the pointer 68 and the scale 69 being so arranged that when the arm 66 is thus adjusted the pointer 68 will register with the zero mark on the scale 69. The gear 70 is rotated into an arbitrary zero position, as shown by the pointer 196 on the dial 197, and the gear 79 will then be in a given position and the zero mark of the graduations 77 of the dial 76 will then register with a fixed pointer 78, the dials 197 and 76 being suitably graduated and arranged to permit of such an adjustment. The switch 89 is then closed, thus rendering the telescope 40 operative to control the predirecting system.

The two pointers 196 and 200 are each then rotated in the same direction from their zero points through the same angle 238 which the line of direction 237 of the target 235 makes with the longitudinal axis 239 of the torpedo boat 9, the direction of rotation of the pointers 190 and 200 depending upon the direction of the course of the target with respect to the longitudinal axis of the torpedo boat. The arrangement is such that a rotation of the pointer 196 in a clockwise direction through any given angle will cause a rotation of the corresponding gear 70 in a counter-clockwise direction and through but half of the given angle, and a rotation of the pointer 200 through a given angle in a clockwise direction will cause a rotation of the corresponding gear 115 in a counter-clockwise direction and through but half of the given angle. The switch 189 which has been left open up to this time is now closed. The sleeve 150 is now moved longitudinally of the arm 110 until the distance 240 from the longitudinal axis of the pivot 152 to the axis of oscillation of the arm 110 is proportional to the known speed of the torpedo 15, as indicated by the scale 111 on the arm 110 which is laid off in knots. The sleeve 150 is now clamped rigidly in position upon the arm 110 by means of a set 130

screw 151. The box 96 containing the secondary transmission system 95 is then moved along the two tracks 55 and 56 until the distance 245 between the axes of oscillation of the two arms 66 and 110 as measured along the graduations 57 provided therefor on the track 55 is equal to the known speed of the target 235. The telescope 40 is now sighted upon the target 235 and the rotation of the telescope about its vertical axis is transmitted by the transmitter 85 to the repeater 80 and by the repeater 80 to the vertical shaft 75. This rotation of the shaft 75 acts through the differential 74, 72, 73, which constantly subtracts the angle 238 from the angle 250 (see Fig. 3) which is given by the telescope 40 and causes the shaft 65 to rotate the arm 66 into such a position that the longitudinal axis of this arm 66 will make an angle 251 with the line joining the axes of oscillation of the two arms 66 and 110 which will be equal to the angle 250 minus the hereinbefore described angle 238, in which the angle 250 is the exterior angle between the longitudinal axis 239 of the torpedo boat 9 and a line 252 drawn through the telescope 40 and the target 235. This rotation of the arm 66 acts through the carrier 155 and sleeve 150 to rotate the upper arm 110 into such a position that the angle 255 between the arm 110 and the line connecting the axes of oscillation of the two arms 66 and 110 will be equal to an angle 253 (see Fig. 3) plus the hereinbefore described angle 238 in which the angle 253 is the angle between the longitudinal axis of the torpedo boat 9 and a line 254 drawn through the telescope 40 and a point 256 in the line of direction 237 of movement of the target 235, and at which point 256 the torpedo 15 should hit the target when the torpedo is predirected and launched to proceed along the line 254. This angle 253 plus 238 of the arm 110 will be transmitted through the differential comprising the beveled gears 118, 117 and 119 in such a manner as to constantly subtract the angle 238 and to cause to shaft 120 to be rotated through an angle equal to the angle 253, and this angle 253 will be transmitted through the transmitter 142, four-wire cable 144 and repeater 143 to the gear 149, which controls the steering mechanism 10 of the torpedo 15 and which will predirect the torpedo in such a manner that when it is discharged it will seek and proceed upon a course along the line 254 and will meet the target 235 at the point 256.

Although only a single form has been shown in which this invention may be embodied, it is to be understood that the invention is not limited in its application to any specific construction but might be embodied in various forms without departing

from the spirit of the invention or the scope 65 of the appended claims.

Having thus fully described my invention, I claim:

1. A predirecting system comprising a primary element arranged to swing about a 70 normally fixed axis, a secondary element arranged to swing with respect to said primary element about a normally fixed axis spaced from said first mentioned axis, means operatively connecting said elements to cause 75 said secondary element to be moved as a result of the movement of said primary element, a sighting unit arranged to control said primary element, and means controlled by said secondary element for predirecting 80 a movable body.

2. A predirecting system comprising a primary element arranged to swing about a normally fixed axis, a secondary element arranged to swing with respect to said primary 85 element about a normally fixed axis spaced from said first mentioned axis, means operatively connecting said elements to cause said secondary element to be moved as a result of the movement of said primary 90 element, and means controlled by said secondary element for predirecting a movable body, said elements being adjustable to vary the distance between said axes.

3. A predirecting system comprising a 95 primary element arranged to swing about a normally fixed axis, a secondary element arranged to swing with respect to said primary element about a normally fixed axis parallel to said first-mentioned axis, means operatively connecting said elements to cause 100 said secondary element to be moved as a result of the movement of said primary element, a sighting unit arranged to control said primary element, and means controlled 105 by said secondary element for predirecting a movable body.

4. A predirecting system comprising a primary element rotatable about a normally fixed axis, a secondary element rotatable 110 with respect to said primary element about a normally fixed axis spaced from said first mentioned axis, means operatively connecting said elements to cause said secondary element to be rotated about its said axis as 115 a result of the rotation of said primary element about its said axis, said means being adjustable to permit each of said elements to be rotated independently of the other of said elements and into an initial position of adjustment, a sighting unit arranged to control said primary element, and means controlled by said secondary element for predirecting a movable body.

5. A predirecting system comprising a primary element rotatable about a normally fixed axis, a secondary element rotatable with respect to said primary element about a nor-

normally fixed axis parallel to said first-mentioned axis, means operatively connecting said elements to cause said secondary element to be rotated about its said axis as a result of the rotation of said primary element about its said axis, said means being adjustable to permit each of said elements to be rotated independently of the other of said elements and into an initial position of adjustment; a 10 sighting unit arranged to control said primary element, and means controlled by said secondary element for predirecting a movable body.

6. The combination with a movable carrier 15 of a predirecting system carried thereby and comprising a primary element arranged to swing about a normally fixed axis, a secondary element arranged to swing with respect to said primary element about a fixed 20 axis spaced from said first mentioned axis, means operatively connecting said elements to cause said secondary element to be moved as a result of the movement of said primary element, a sighting unit arranged to control 25 said primary element, means controlled by said secondary element for predirecting a dirigible body while said body is mounted upon and movable with respect to said carrier, and stabilizing means automatically 30 acting to modify the movement of said primary element and to vary the predirecting effect of said secondary element.

7. The combination with a movable carrier 35 of a predirecting system carried thereby and comprising a primary element arranged to swing about a normally fixed axis, a secondary element arranged to swing with respect to said primary element about a fixed axis spaced from said first mentioned axis, means 40 operatively connecting said elements to cause said secondary element to be moved as a result of the movement of said primary element, a sighting unit arranged to control said primary element, means controlled by 45 said secondary element for predirecting a dirigible body while said body is mounted upon and movable with respect to said carrier, and stabilizing means including a gyroscope 50 automatically acting to modify the movement of said primary element and to vary the predirecting effect of said secondary element.

8. The combination with a movable carrier 55 of a predirecting system carried thereby and comprising a primary element arranged to swing about a fixed axis, a secondary element arranged to swing with respect to said primary element about an axis spaced from said first mentioned axis, means operatively 60 connecting said elements to cause said secondary element to be moved as a result of the movement of said primary element, said means being adjustable to permit each of said elements to be given a variable initial 65 adjustment independently of the other of

said elements, a sighting unit, stabilizing means arranged to cooperate with said sighting unit for controlling the movement of said primary element, and means jointly controlled by said secondary element and said stabilizing means for predirecting a movable body.

9. The combination with a movable carrier 70 of a predirecting system carried thereby and comprising a primary element arranged to swing about a fixed axis, a secondary element arranged to swing with respect to said primary element about an axis spaced from said first mentioned axis, means operatively 75 connecting said elements to cause said secondary element to be moved as a result of the movement of said primary element, said means being adjustable to permit each of said elements to be given a variable initial adjustment independently of the other of said elements, a sighting unit, stabilizing means including a gyroscope arranged to cooperate with said sighting unit for controlling the movement of said primary element, and means jointly controlled by said secondary element and said stabilizing means for predirecting a movable body.

10. The combination with a movable carrier, of a predirecting system carried thereby and comprising a primary element, a secondary element movable with respect to said primary element, means operatively connecting 95 said elements to cause said secondary element to be moved as a result of the movement of said primary element, said means being adjustable to permit each of said elements to be moved independently of the other of said elements, a sighting unit, and stabilizing means including a gyroscope arranged to cooperate with said sighting unit 100 to control the movement of said primary element, and means jointly controlled by said secondary element and said stabilizing means for predirecting a movable body.

11. The combination with a movable carrier 110 of a predirecting system carried thereby and comprising a primary element arranged to swing about a normally fixed axis, a secondary element arranged to swing with respect to said primary element about a normally fixed axis parallel to said first-mentioned axis, said elements being adjustable to vary the distance between said axes, means operatively connecting said elements to cause said secondary element to be rotated about its said axis as a result of the rotation of said primary element about its said axis, a sighting unit, stabilizing means arranged to cooperate with said sighting unit to determine the position of said primary element, and predirecting means for a movable body jointly controlled by said secondary element and said stabilizing device.

12. The combination with a movable car- 130

- rier, of a predirecting system carried thereby and comprising a primary element arranged to swing about a normally fixed axis, a secondary element arranged to swing with respect to said primary element about a normally fixed axis parallel to said first-mentioned axis, said elements being adjustable to vary the distance between said axes, means operatively connecting said elements to cause said secondary element to be rotated about its said axis as a result of the rotation of said primary element about its said axis, said means being adjustable to permit each of said elements to be rotatably adjusted about its said axis independently of the other of said elements, a sighting unit, stabilizing means arranged to cooperate with said sighting unit to determine the position of said primary element, and predirecting means for a movable body jointly controlled by said secondary element and said stabilizing means.
13. The combination with a movable carrier, of a predirecting system carried thereby and comprising a primary element arranged to swing about a normally fixed axis, a secondary element arranged to swing with respect to said primary element about a normally fixed axis parallel to said first-mentioned axis, said elements being adjustable to vary the distance between said axes, means operatively connecting said elements to cause said secondary element to be rotated about its said axis as a result of the rotation of said primary element about its said axis, a sighting unit, stabilizing means including a gyroscope arranged to cooperate with said sighting unit to determine the position of said primary element, and predirecting means for a movable body jointly controlled by said stabilizing means and said secondary element.
14. The combination with a movable carrier, of a predirecting system carried thereby and comprising a primary element arranged to swing about a normally fixed axis, a secondary element arranged to swing with respect to said primary element about a normally fixed axis parallel to said first-mentioned axis, said elements being adjustable to vary the distance between said axes, means operatively connecting said elements to cause said secondary element to be rotated about its said axis as a result of the rotation of said primary element about its said axis, said means being adjustable to permit each of said elements to be rotatably adjusted about its said axis independently of the other of said elements, a sighting unit, stabilizing means including a gyroscope arranged to cooperate with said sighting unit to determine the position of said primary element, and predirecting means for a movable body jointly controlled by said stabilizing means and said secondary element about a normally fixed axis parallel to said first-mentioned axis, said elements being adjustable to vary the distance between said axes, means operatively connecting said elements to cause said secondary element to be rotated about its said axis as a result of the rotation of said primary element about its said axis, said means being adjustable to permit each of said elements to be rotatably adjusted about its said axis independently of the other of said elements, a sighting unit, stabilizing means arranged to cooperate with said sighting unit to determine the position of said primary element, and predirecting means for a movable body jointly controlled by said stabilizing means and said secondary element.
15. A predirecting system for a movable body, comprising a primary arm rotatable about a normally fixed axis, a secondary arm rotatable with respect to said primary arm about a normally fixed axis parallel to said first-mentioned axis, means normally fixedly secured to said secondary arm and engaging said primary arm and normally freely movable longitudinally thereof to cause said secondary arm to be moved as a result of the movement of said primary arm, a sighting unit arranged to control said primary arm, and means controlled by said secondary arm for predirecting said movable body.
16. A predirecting system for a movable body, comprising a primary arm rotatable about a normally fixed axis, a secondary arm rotatable with respect to said primary arm about a normally fixed axis parallel to said first-mentioned axis, means normally fixedly secured to said secondary arm and engaging said primary arm and normally freely movable longitudinally thereof to cause said secondary arm to be moved as a result of the movement of said primary arm, said means being adjustable longitudinally of said secondary arm to compensate for variations in the speed of said movable body, a sighting unit arranged to control said primary arm, and means controlled by said secondary arm for predirecting said movable body.
17. A predirecting system for a movable body, comprising a primary arm rotatable about a normally fixed axis, a secondary arm rotatable with respect to said primary arm about a normally fixed axis parallel to said first-mentioned axis, said arms being adjustable to vary the distance between said axes to compensate for variations in the speed of a target and said arms being separately adjustable rotatably to compensate for relative variations in the initial position of and the initial direction of movement of the target, means normally fixedly secured to said secondary arm and engaging said primary arm and normally freely movable longitudinally thereof to cause said secondary arm to be moved as a result of the movement of said primary arm, a sighting unit arranged to control said primary arm, and means controlled by said secondary arm for predirecting said movable body.
18. A predirecting system for a movable body, comprising a primary arm rotatable about a normally fixed axis, a secondary arm rotatable with respect to said primary arm about a normally fixed axis parallel to said first-mentioned axis, said arms being adjustable to vary the distance between said axes to compensate for variations in the

speed of a target and said arms being separately adjustable rotatably to compensate for relative variations in initial position of and in the initial direction of movement of the target, means normally fixedly secured to said secondary arm and engaging said primary arm and normally freely movable longitudinally thereof to cause said secondary arm to be moved as a result of the movement of said primary arm, said means being adjustable longitudinally of said secondary arm to compensate for variations in the speed of said movable body, a sighting unit arranged to control said primary arm, and means controlled by said secondary arm for predirecting said movable body.

19. The combination with a movable body, of means carried thereby for propelling said body at a given rate, automatic steering means carried by said body, and means for adjusting said steering means, including two elements rotated one by the other and arranged to swing respectively about two predetermined parallel axes, and 25 a sighting element arranged to control one of said elements so as to predirect said body in such a manner as to cause said body when launched at a given moment to seek and pro-

ceed upon a predetermined course which will cause said body to strike while on said course a target located at said moment in a given position and moving and continuing to move from said position in a known and fixed direction at a known and fixed rate.

20. The combination with a movable body of means carried thereby for propelling said body at a given rate, automatic steering means carried by said body, a sighting device, and means arranged to be controlled by said sighting device, and including two 40 elements arranged to swing about two parallel axes respectively for predirecting said steering mechanism in such a manner as to cause said body when launched at a given moment to seek and proceed upon a predetermined course which will cause said body to strike while on said course a target located at said moment in a given position and moving and continuing to move from said position in a known and fixed direction at a 45 known and fixed rate.

Signed at New York, in the county of New York and State of New York this 16th day of February, A. D. 1918.

ALBERT D. TRENOR.
